UNITED STATES PATENT OFFICE.

JAMES F. INGRAHAM, OF WEST PEABODY, MASSACHUSETTS.

LIFE-GUARD OR FENDER FOR CARS.

SPECIFICATION forming part of Letters Patent No. 511,432, dated December 26, 1893.

Application filed October 29, 1892. Serial No. 450,325. (No model.)

To all whom it may concern:

Be it known that I, JAMES F. INGRAHAM, of West Peabody, in the county of Essex and State of Massachusetts, have invented certain 5 new and useful Improvements in Life-Guards or Fenders for Cars, of which the following is a specification.

This invention has relation to life-guards for railway cars, and is particularly adapted 10 for use on electric and other street cars operated by power.

It is the object of the invention to provide such improvements in life-guards or fenders as will with certainty prevent a person or object met with upon the track from passing 15 under the wheels or truck-frame of the car.

The invention consists in providing the truck-frame with a scoop-guard hinged thereto in front of the wheels, and which may be 20 normally supported at a safe distance above the road-bed, combined with a swinging-guard so connected with the scoop-guard as that when the swinging-guard encounters an object on the track it will release the scoop-guard and allow the forward end thereof to 25 drop down on the track, and, as it were, scoop up such object and with certainty prevent the same from passing under the truck frame or wheels of the car, all as is hereinafter described and claimed.

Reference is to be had to the annexed drawings and to the letters marked thereon, forming a part of this specification, the same letters designating the same parts or features, 35 as the case may be, wherever they occur.

Figure 1, is a perspective view of the invention, showing it attached to the truck frame of the car, together with the forward wheels and axle of the latter. Fig. 2, is a longitudinal sectional view, showing the scoop-guard 40 in raised or normal position. Fig. 3, is a similar sectional view, showing the scoop-guard as released and lowered, and the swinging-guard as moved by contact with the feet of a person on the track.

In the drawings, *a a* represent the wheels, *b b* the rails upon which the wheels travel, and *c* the truck-frame.

d designates a frame with which the various parts of my improvement are connected, the said frame being connected with the truck-frame and extending in front of the wheels.

e is what I have chosen to term the "scoop-guard," which may be pivotally supported at its rear end upon the truck-frame or upon the 55 frame *d*, the said scoop-guard consisting of a broad sheet of metal or other suitable material sufficient in extent to support and carry upon it the body of a man. The supporting part *f* of the scoop-guard extends horizontally, and its front edge is preferably, though not necessarily scalloped or otherwise formed so as that the said edge may not be straight, in order the better to adapt it to scoop or catch up an object encountered by it. The 60 back part *g* of the scoop-guard extends vertically at substantially a right angle to the supporting part, and is hinged, as at *h*, to the frame.

i is a bar connected with the upper edge of 70 the back part of the scoop-guard, and *j* designates springs connected with the said bar and the frame *d*, and operating with a tendency to draw the upper edge of the back part of the scoop-guard forward, rocking the latter 75 on its pivot or hinge and lowering the scalloped lower end thereof upon the track.

k is a swinging-guard pivoted upon the forward end of the frame *d*, the said swinging-guard consisting of a frame in which are arranged independent vertically movable bolts or rods, so that the said bolts or rods may be drawn upward to assist in extricating a person or object over or upon which the swinging guard may have chanced to pass. 85

l designates bars centrally pivoted upon the frame *d*, and arranged so that normally their rear ends may bear against the bar *i* and their forward ends rest upon the broad flat bar *m* of the swinging-guard. Springs *n* connected 90 with the frame *d* are arranged to bear upon the forward ends of the bars *l* and hold the same down upon the bar *m*.

o is a lever pivoted upon the frame *d* and having connected therewith one end of a pitman or bar *p*, the other end being connected with the bar *i*. 95

With this description supposing the parts to be arranged as shown in Figs. 1 and 2, the device will be in its normal position. In case 100 an unusual object is encountered on the track, the bolts of the swinging-guard will strike said object, move the swinging-guard upon its pivots, raise the forward ends of the

bars *l*, lowering their rear ends so as that they may pass under the bar *i* and allowing the springs *j* to act upon the scoop-guard so as to lower its forward end upon the track or road-bed, as shown in Fig. 3, thus putting the scoop-guard in position to catch or scoop up upon its holding part the object encountered, all as will be readily understood without further description.

- 10 To restore the scoop-guard to normal position the operator may but take hold of the outer end of the lever *o*, move the same backward, pushing the back part *g* of the scoop-guard in the same direction through the medium of the pitman *p* until the rear ends of the bars *l* snap up against the forward face of the bar *i*.

Having thus explained the nature of the invention and described a way of constructing and using the same, though without attempting to set forth all of the forms in which it may be made or all of the modes of its use, it is declared that what is claimed is—

1. A life-guard for railway cars comprising 25 in its construction a swinging-guard consisting of a frame provided with independent vertically movable bolts or rods, a pivoted or hinged scoop-guard, and connections between the swinging-guard and scoop-guard, whereby 30 when the former encounters an obstruction, it may unhinge or release the latter, as set forth.

2. A swinging-guard for railway cars consisting of a frame provided with independent vertically movable bolts or rods, as set forth. 35

3. In a car guard the combination of a pivoted or hinged scoop-guard, springs arranged to normally depress said scoop-guard, pivoted locking levers *l l* arranged to engage said scoop-guard, and support the same in a raised 40 position against the pressure of said springs, and a swinging-guard engaged with the forward ends of said locking levers, and adapted when displaced, to displace said locking levers and thereby release the scoop-guard, as 45 set forth.

4. In a car guard the combination of a pivoted or hinged scoop-guard, springs arranged to normally depress the same, locking devices adapted to engage said scoop and lock it in 50 a raised position, means for displacing said locking devices to release the scoop and permit its depression by the springs, and an operating lever whereby the scoop may be raised and re-engaged with the locking devices, as 55 set forth.

In testimony whereof I have signed my name to this specification, in the presence of two subscribing witnesses, this 12th day of October, A. D. 1892.

JAMES F. INGRAHAM.
